OYSTER SHUCKING KNIFE

Charles D. Briddell, 335 Hill-N-Dale Drive,
York, Pa. 17403

Filed July 5, 1972, Ser. No. 269,070

Term of patent 7 years

Int. Cl. D7—03

U.S. Cl. D7—150

FIG. 1 is a top rear perspective view of an oyster shucking knife showing my new design.

FIG. 2 is a bottom front perspective view thereof.

FIG. 3 is a bottom plan view thereof.

FIG. 4 is a top plan view thereof.

FIG. 5 is an end elevation thereof as seen from the right of FIG. 3.

I claim:

The ornamental design for an oyster shucking knife, as shown.
